H. B. DONLEY

HEADLIGHT FOR AUTOMOBILES

Filed Oct. 27, 1922

Inventor

Harold B. Donley

By C. C. Shepherd
Attorney

UNITED STATES PATENT OFFICE.

HAROLD B. DONLEY, OF COLUMBUS, OHIO, ASSIGNOR TO THE JOHN W. BROWN MANUFACTURING COMPANY, OF COLUMBUS, OHIO, A CORPORATION OF OHIO.

HEADLIGHT FOR AUTOMOBILES.

Application filed October 27, 1922. Serial No. 597,346.

To all whom it may concern:

Be it known that I, HAROLD B. DONLEY, a citizen of the United States, residing at Columbus, in the county of Franklin and 5 State of Ohio, have invented certain new and useful Improvements in Headlights for Automobiles, of which the following is a specification.

The present invention relates to improvements in head lights for automobiles.

The primary object of the invention is to provide novel means for tilting the reflector of the headlight so that the light rays thereof can be deflected in such directions as to prevent glaring.

A further object of the invention is to provide a headlight so constructed that the reflector can be easily and quickly tilted and held positively in its tilted position in a 20 convenient manner.

With these and other objects in view, as will appear as the description proceeds, the invention consists in the novel features of construction, combinations of elements, and 25 arrangements of parts, and hereinafter to be fully described and pointed out in the appended claim.

In the accompanying drawing:

Figure 1 is a vertical central sectional view through a headlight equipped with the device,

Figure 2 is a fragmentary horizontal view taken through the headlight and showing the tilting mechanism in top elevation, and

Figure 3 is a sectional view on the line 3—3 of Figure 1.

Referring to the drawing 1 designates the casing which is of any well known form and is provided with the usual lens 2, said casing being mounted upon the automobile in 40 any suitable manner.

The reflector 3 is of the parabolic type and is pivotally supported within the casing 1 by brackets 4 which may be of any suitable 45 construction. The reflector has associated therewith the incandescent bulb 5 which is mounted in a socket 6 carried by the reflector, said socket having a plate 7 connected therewith and to which is connected 50 the lower end of the coil spring 8, the upper end of said spring being connected with the top of the casing 1, said spring serving to yieldably hold the reflector 3 in its tilted or normal position.

55 Mounted upon the bottom of the casing 1

is a housing 9, said housing having an annular groove 10 formed therein and in which is located a coil spring 11, the purpose of which will appear later. This housing has formed integral therewith a block 12.

To the lower end of the reflector 3 is riveted a bracket 13 which is provided with spaced ears 14, and between which is pivotally connected the forward end of the rod 15, said rod being slidable in bearings 16 formed in the ends of the housing 9. This rod is provided centrally with a head 17, said head being longitudinally curved so that it will be held in adjusted positions within the housing 9 when the rod 15 is 70 shifted. As shown in Figure 1 of the drawing the head is in its rearmost position and at which time the coil spring 11 is engaged with the forward end of said head thus holding the shaft 15 in the position as shown, in 75 an obvious manner. When it is desired to move the reflector 3 to its normal position it is only necessary to shift the rod 15 forwardly whereupon the spring 11 will engage the rear end of the head 17, thereby holding 80 the rod 15 in its forward position. As shown in Figure 1 the reflector is in its tilted position, and as before stated the head 17 is in its rearmost position.

The block 12 is provided with a bearing 85 18 which has its lower end opening into an annular recess 19 also formed in the block and in which is rotatably mounted the collar 20 of the shaft 21, the upper end of the shaft 21 being rotatable in the bearing 18. 90 Since the collar 20 is located in the recess 19 upward movement of the shaft 21 is prevented, and since the collar rests upon the bottom of the casing 1 downward movement of said shaft is prevented, but the shaft is 95 permitted to turn freely within its bearing when described. The upper end of the shaft 21 has fixed thereto in any suitable manner the arm 22, said arm being provided with furcations 23 between which is pivotally 100 connected the rear end of the rod 15. The lower end of the shaft 21 terminates in an angularly disposed arm 24 which has pivotally connected thereto the forward end of the link 25, said link being extended rearwardly so that it can be conveniently manipulated by the driver of the car to operate the reflector when desired.

It will be obvious that when the rod 15 is in the position as shown in Figure 1 that 110

the rays from the light 5 will be deflected downwardly, and when it is desired to return the reflector 3 to its normal position it is only necessary to move the link 25 forwardly wheretupon the shaft 21 will be rocked and consequently the arm 22 will be swung forwardly thus compelling the rod 15 to move forwardly until the head 17 carried thereby is in the forward end of the 10 housing 9, and at which time the spring 11 will serve to hold the head against accidental rearward movement.

From the foregoing description it will be apparent that a simple and efficient means 15 has been provided for reciprocating the rod 15 to move the reflector to its tilted position when desired, and return the same to its normal position after the light rays have been deflected downwardly. Further it will be 20 observed that by mounting the shaft 21 in the manner shown that entrance of moisture

and dust to the interior of the casing is prevented.

What is claimed is:

In combination with a lamp casing, a reflector mounted therein for tilting movement, a housing mounted within the casing, a rod slidably mounted in the housing and having its forward end pivotally connected with the reflector, a block mounted in the 25 casing adjacent the housing and having a bearing formed therein, a shaft rotatably mounted in the bearing and having a laterally disposed arm carried by its upper end, said arm being pivotally connected to the rear end of the rod, and a link pivotally connected with the lower end of the shaft to rotate the same to shift the rod to control the tilting movement of said reflector 30

In testimony whereof I affix my signature,

HAROLD B. DONLEY.
